Wernerwerk, Siemensstadt, near Berlin, Germany

Application July 8, 1937, Serial No. 152,552
In France July 22, 1936

30 Claims. (Cl. 179—7.1)

The present invention relates to a circuit arrangement for telephone systems with registers. It concerns the arrangement of a register in a telephone system having a plurality of exchanges and concerns the particular construction of the register, which is provided with various approaches, the mode of operation of the register being adapted to various requirements in accordance with the characterization of these approaches on the establishment of a call between the various exchanges. The register itself is provided with devices which enable an impulse train transmitted to the register to be used for transmitting separate signals which do not serve for setting switches. A complete suppression of the impulse train can take place instead of the transmission of a signal. A further characteristic of the invention consists in that the register transmits "ready" impulses before receiving individual impulse trains in accordance with the manner in which the approaches are characterized. Moreover, by characterizing particular approaches the assessing device can be set out of action. When the assessing device is used the mode of transmission of "ready" impulses can be different.

The use of registers equipped in accordance with the invention is particularly advantageous in systems in which the signalling of impulses over connection lines is effected by alternating current. Further characteristics of the invention are set out in the drawings and description.

Fig. 1 shows diagrammatically in the form of a circuit layout the arrangement of the register (Reg. 3) shown in detail in Figs. 2 and 2A. This register is connected up on incoming calls in that, for example, in the case of calls over one of the lines B₁ to B₆, one of the secondary switches 11-16 is set on the connecting repeater Ue. According to the embodiment the secondary switch is set by the transmission of an A. C. seizing impulse. When the repeater Ue has been seized a free register is connected up over the switch 17. As may be seen from Fig. 1, the connecting repeater Ue possesses a plurality of approaches some of which are reached by the switches 11-14 and others by the switches 15 and 16. In accordance with the seizure of the connecting repeater over one of these approaches switching operations take place in the register which influence the mode of operation of the latter in a particular way. Thus for example when the register is seized by way of the secondary switch 15 only four of the impulse trains received by the register are transmitted unal-

tered, a revertive impulse being transmitted to the calling station before each impulse train sent to the register. If the register is seized over the switches 11-14 five impulse trains are sent in to the register, of which the third impulse train is converted for the purpose of transmitting special signals. This third impulse train consists of one or two impulses according to the embodiment. If only one impulse is sent in to the register it is suppressed. If, however, two impulses are sent in to the register as the third impulse train these effect a reversal of current over the leads of the connecting line whereby a particular meter is connected to the connecting line. By these means incoming calls in a particular direction are dealt with in a different way from calls coming in over the same line from another direction. Such special treatment may be necessary for various reasons for example in the case of calls from a distant exchange. In the case of such calls only a single "ready" impulse is transmitted before the commencement of the reception of impulses by the register.

Naturally instead of connecting a special meter a special lamp may be connected up in order, for example, to indicate to an operator when a call has been set up from a particular direction and that she must listen in to this call. It is not necessary for the digits 1 and 2 to be used for differentiation. Naturally any digits could be used.

If the register is seized over the switch 16 the register is set in readiness for five impulse trains of which the third is used for transmitting special signals. In this case the manner of transmitting revertive impulses when the receiving switches of the register are in the ready condition is different from the case when the register is seized over the switches 11-14 in which case also five impulse trains are taken up by the register. Thus in the present case revertive impulses are transmitted before the reception of the first, second, third and fifth impulse trains. The third impulse train is used in this case in the same way as in the case in which the register is taken into use over the switches 11-14.

The transmission of impulses for setting the group selector IIIGW3 commences when the register is only partly set, and later the switch IIIGW and the switch LW to which the desired subscriber is connected are set in succession. When the wanted party replies the metering switch determined by the register is influenced by switching means in the connecting repeater Ue.

- the calling and numerical impulses which are associated with the lines B1 to B6 are not shown since these have been described as known. The local traffic proceeding over switches IIIGW and 5 LW comes from the group selectors IGW1 and IIGW4 without the aid of registers. Outgoing calls over the lines B1 to B5 are established with the help of the register Reg. 2. The line B6 is only adapted for incoming calls.
- 10 Calls in the direction A proceed over the levels 3 and 4 of the group selector IGW1 with the aid of the register Reg. 1, while calls passing in the direction A over level 4 of the group selector IIGW2 and level 5 of the group selector IIGW1 15 are set up by the aid of the register Reg. 2. The establishment of an incoming call over the connecting line B4 will first be described with reference to Fig. 2 and then the establishment of incoming calls over the lines B5 and B6.
- 20 If a call is to be set up over the line La, Lb the seizing impulse for initiating the call is transmitted by alternating current. This alternating current is transmitted to relay MR1 by the transformer Ue1. A rectifier GL is arranged in parallel 25 with relay MR1. Relay MR1 operates its contacts 2mr1 and 3mr1. Contact 2mr1 opens a point in the circuit for relay MU. Contact 3mr1 energizes relay MR in the following circuit: earth, contact 3mr1, MR, battery and earth.
- 30 Relay MR operates its contacts 4mr to 9mr. Contact 4mr applies battery to the rotary magnet MD over contacts 4mr, 15mx, 18mz and 12mt so that the magnet is impulsively operated by the interrupter Un1. The magnet MD operates 35 its wipers am, bm, cm, dm, and em. Moreover, each time the rotary magnet MD operates it actuates contact 1md. Contact 5mr is closed while contacts 6mr and 1mr are opened. Through the closing of contact 5mr the circuit in which 40 relay MR1 energizes is maintained. Contact 8mr applies earth to windings I and II of relay MT. Contact 9mr short-circuits relay MX.
- During the transmission of alternating current the switch MW is now stepped forward until its 45 wiper cm rests on a free line. If wiper cm finds the line shown for example at contact Cd to be the first free line the following circuit is established: earth, contact 8mr, windings I and II of relay MT, lead Lc, wiper cm, the connection between contacts cd and Cd, which is not shown, 50 resistance Wi3, contact 23k which is closed in the normal condition of the system, contacts 45s and 180z, resistance Wi4, winding II of relay C, battery and earth. In this circuit relays 55 MT and C energize. Relay MU is connected to wiper dm by contact 10mt. At contact 11mt a locking circuit is established by the application of earth to winding II of relay MT. Winding I of relay MZ which is disposed in series 60 with winding II of relay MT does not energize in the circuit just described. The switch MD is brought to rest through the opening of contact 12mt. Contacts 13mt and 14mt are switched over but this does not produce any switching 65 operation. If the transmission of alternating current to relay MR1 has not yet terminated the alternating current cannot influence succeeding devices in spite of contacts 13mt and 14mt having been switched over because contacts 6mr and 1mr are still open. The speaking leads are 70 only switched through when the transmission of alternating current from the calling station is terminated and relays MR1 and MR have released. The alternating current repeater seized 75 by the energizing of relay C (winding II) is provided with a connecting switch DW having an associated rotary magnet WD. This magnet operates wipers aw, aw1, cw, cw1, cw2, dw and ew. In addition the magnet WD possesses a contact wd which is only operated when the magnet 5 WD is energized.
- If when a call is initiated the switch MW does not find a free outgoing line it advances into position 17. In this position relay MT operates since it finds battery over contacts 9mr and 10 16mx, and resistance Wi2. Relay MT brings the switch to rest by way of contact 12mt. At the end of the transmission of alternating current relays MR1 and MR release. When contact 9mr is open relay MX energizes. Relay MX operates 15 its contacts 15mx to 17mx. Contact 15mx opens the circuit of magnet MD. Contact 16mx connects up earth in preparation. Contact 17mx is opened. If now a seizing impulse is again transmitted over the line La, Lb relays MR1 and 20 MR energize again. Hereupon relay MX is held energized by the closing of contact 9mr over earth, contact 16mx, relay MX, resistance Wi2, battery and earth while relay MT is short-circuited by the earth connected to contact 16mx. 25
- Relay MT consequently releases and closes contact 12mt. When the alternating current passing over the leads La and Lb is disconnected relays MR and MR1 also release. When relay MX releases the rotary magnet MD receives the 30 impulse occasioned by the closing of contact 15mx whereby the switch is advanced to position 0. From this position it can then be started up by the transmission of a fresh alternating current impulse over the line La, Lb in the 35 manner already described. Successive transmission of alternating current seizing impulses can proceed for a definite time and only after the expiry of this period is a busy signal transmitted to the calling station. The automatic transmission is brought to an end by an alternating current impulse sent back when a free register is prepared. If a very short alternating current impulse is transmitted on initiating a call as 40 may occur when using automatic calling devices when these are connected up the switch is unable to test when relay MR is released in the event of the switch MW not having found a free line before the termination of this impulse. The switch then advances automatically to position 0 being controlled over wiper em. From 45 this position it is then started up in the normal way by the next seizing impulse. As has been previously mentioned relay K is energized in the normal condition of the alternating current repeater. The circuit for this relay passes from earth over wiper ew and winding I of relay K to the lead Lc2 and battery in the group selector reached over the leads La2, Lb2, and Lc2. Contact 23k has prepared the test circuit. The other 50 contacts of relay K have been opened or closed or switched over without provoking any special switching operations. The contacts 29c to 33c are operated by the energizing of relay C when the alternating current repeater was seized. 55 Contact 29c connects up winding I to relay C in preparation. Contact 32c prepares a testing circuit for the connecting switch DW for connecting a free register. Over contact 70q contact 33c connects winding I of relay B to the terminal Ad which is connected to the terminal ad. Relay B is energized on the closing of contact 60 33c by the earth connected to wiper dm. Relay MU does not energize since being in series with winding I of relay B it does not receive sufficient 65
- 70
- 75

current. Relay B operates contacts 34b to 38b. Contact 34b brings about the energizing of relay E over earth, battery, resistance W11, relay E, contacts 68q, 34b and 30c and earth. Contact 35b prepares a locking circuit for winding II of relay B which, however, only becomes effective after relay Q has operated. Contact 36b prepares a locking circuit for the register. Contact 37b opens a point in the circuit of the lamp AL. Contact 38b in the lead Ld is closed. Relay E locks up at contact 39e. Contact 40e switches on winding I of relay C. Contact 41e short-circuits winding II of relay C1. Contact 43e short-circuits winding I of relay K which releases. Contact 44e connects up lead La2 for the outgoing impulse transmission. The release of relay K remains without effect until winding II of relay S is energized. Relay S (winding II) is energized in the following circuit: earth, contacts 28k, 42e, 52p, and 69q, wd, winding II of relay S, battery and earth. Relay S operates contacts 45s to 49s. Contact 47s short-circuits the thermo-relay Th. Contact 48s prepares for the energizing of winding III of relay S. Contact 49s causes the earth connected up at 28k to be connected to the rotary magnet WD. This latter energizes and operates contact wd. Hereupon relay S (winding II) releases. Contact 49s disconnects the magnet WD. The contact wd on releasing reenergizes winding II of relay S. This interaction continues, the wipers of switch WD being thereby advanced until a free register is found. If the register shown in the drawings is free the following test circuit is established: earth, contacts 32c and 99q, winding II and I of relay P, 79c1, cw, Sc, W19, 102f, 103rc, winding II of relay RC, battery and earth. In this circuit relays P and RC energize. The seizure of the register over wiper cw indicates that the register is to deal with five impulse trains of which the third is used for sending out special signals. Moreover the connection of the register over wiper cw determines that the latter is only to transmit a single revertive impulse.

When relay P operates it actuates contacts 50p to 58p and 100p. Contact 50p by applying earth directly over contacts 32c, 36b and 50p to winding I of relay P guards the seized register. Contact 51p connects winding II of relay U to wiper aw. Contact 52p brings the switch DW to rest by breaking the stepping circuit of the rotary magnet WD. Contact 53p breaks the lead Lb2 and contact 54p switches through the lead Ld. Contact 100p connects the lead Ld serving as an impulse lead for the outgoing impulses to lead La2.

In the register relay RC has been energized. Relay RC prepares the register for the reception of impulses and transmits a signal to the alternating current repeater over contact 135rc by applying earth to the lead Ld to indicate that the register is ready to receive impulses. The earth applied at contact 135rc energizes relay R in the alternating current repeater in the following circuit: earth, contacts 135rc, 144rv, 182.4, wiper 2d4, approach Sd, wiper dw, contacts 54p, 38b, 181z, thermo-relay Th, contact 75h, relay R, resistance W19, battery and earth. Relay R energizes and operates its contacts 55r and 58r. Contact 55r energizes relay R1 which is a slow-acting relay. Contact 56r connects relay Q to the earthed lead Ld. Relay Q energizes. When relay R1 energizes contacts 57r1 to 59r1 are operated. Contacts 51r1 and 58r1 connect the alternating current source We to the

speaking leads so that the alternating current is transmitted over the repeater Ue1 to the line La, Lb. Contact 59r1 connects relay T to the earthed lead Ld by way of contact 181z. Relay T energizes and operates contacts 60t to 65t. Contact 60t short-circuits resistance W14. This, however, does not produce any switching operation. Contact 61t holds relay T energized independently of contact 59r1. Contacts 62t and 63t open the speaking leads. The switching over of contacts 64t does not promote any switching operation. Contact 65t short-circuits relay R. Relay R releases and thereupon relay R1 makes a delayed release. Relay Q does not release since contact 67q has been closed and a locking circuit has been established to the earth connected over contact 31c. Winding II of relay B is also held by this earth when winding I of relay B deenergizes through the opening of contact 70q. On the release of relay R1 the transmission of alternating current to the calling station is terminated. Contact 69q breaks the circuit for winding II of relay S. Contact 99q closes in preparation the circuit for the alarm lamp AL.

The transmission of alternating current from the source We, indicates to the calling station that impulses may be transmitted to the register. This transmission of alternating current when a plurality of calling impulses are transmitted can bring about the termination of the transmission of the calling signal as previously described. The manner in which this alternating current is transmitted to the calling station and the equipment at the calling station does not concern the present invention.

After the application of the "ready" signal by the register to the lead Ld the thermo-relay Th heats up and thus supervises the orderly procedure of the call.

When impulses are transmitted by the calling station after the "ready" signal transmitted from the source of alternating current We has been received the A. C. receiving relay J is impulsively operated. Each time relay J energizes contact 71j is operated so that relay H follows the impulses.

Relay H controls contacts 72h. Contact 72h is closed without controlling any special circuits. Contact 73h connects the earth at contact 30c to relay T (I) over contacts 34b and 68q throughout the impulse transmission so that this relay remains operated even in the event of the earth at contact 135rc being disconnected during the impulsion. Contact 74h short-circuits relay E intermittently without, however, causing it to release. Contact 75h intermittently breaks the heating circuit for relay Th. Contact 76h repeats the incoming impulses to the register. This impulse circuit is completed from earth at wiper ew over contacts 76h and 51p, wiper aw, approach Sd and contact 87rm to relay A, battery and earth in the register.

If the calling station should delay dialling after receiving the "ready" signal which was transmitted by the application of earth to the lead Ld at contact 135rc or after having commenced to dial should delay the transmission of further impulse trains relay Th becomes operative. Relay Th by switching over its contacts 77th energizes winding III of relay S in the following circuit: earth, battery, 111S, contact 77th, lead Ld, contact 38b, contact 54p, wiper dw, Sd, 2d4, 182.4, 144rv, 135rc, and earth. Relay S operates its contacts and locks up at 48s over contacts 66q and 27k and the lead Ld. Contact 75

47s short-circuits relay Th. When relay Th releases the following short-circuit is produced for winding II of relay B: earth on the lead Ld, contacts 27k, 66q, 48s, 77th (raised) contact 26k, 5 winding II of relay B, contacts 35b, 67q, 31c and earth. Relay B in this circuit releases. The seized register is released by the opening of contacts 36b and 38b. The closing of contact 37b switches on a lamp AL which indicates to the 10 exchange staff that the calling station has not proceeded with the establishment of the call in the normal fashion. Relays T and S likewise release since the earth is disconnected at Ld.

If, however, the calling station should commence the further dialling after relay Th has 15 energized but before relay B has released, relay B is prevented from being short-circuited on the release of relay Th in the case of particular calls in that when impulses are transmitted to the 20 register contact 144rv is open and the earth applied at contact 135rc cannot become operative to short-circuit relay B. This case only occurs when the register has been taken into use over the approaches Sc1 or Sc2 as will be described 25 later.

On taking the register into use over the approach sc relay RC was energized over winding II as previously described. Relay RC operates contacts 103rc, 104rc, 127rc, 131rc, 135rc, and 30 172rc. Contact 103rc switched on winding I of relay RC in the testing circuit. Contacts 104rc and 127rc are switched over without promoting any particular switching operation. Contact 131rc short circuits winding I of relay Y. Contact 135rc earths the approach Sd. Contact 35 172rc applies earth to winding I of relay RR. Relay RR energizes and operates contacts 88rr, 106rr, 132rr, 133rr, and 168rr. Contact 88rr breaks the circuit of the impulses to be transmitted from the register. Contact 108rr is opened. 40 Contact 132rr removes the short circuit about winding I of relay Y. Contact 133rr is temporarily closed. Contact 168rr energizes relay RQ. Relay RQ operates contacts 108rq, 124rq, 45 151rq, 153rq, 155rq, and 169rq. Contact 169rq establishes a locking circuit which is independent 50 of the operation of contact 168rr. Contact 124rq temporarily connects earth to the control circuit of the rotary magnets D1 and D4 of the register switches of the register. Contacts 151rq, 153rq and 155rq break circuits in the chain of control switch wipers 3d1 to 3d4 of the register switches. Contact 100rq temporarily connects earth to the circuit over which the outgoing impulses are 55 transmitted from the register.

When now impulses are passed into the register, i. e., when relay A is impulsively operated contacts 123a, 125a, 136a, 148a and 167a are switched over by relay A. Contact 123d sets up 60 the following circuit for the rotary magnet D1 of the first register switch D1; earth, battery, rotary magnet D1, contacts 109.1, 110.2, 121.3, 122.4, 123a, 124rq and earth. Magnet D1 is operated and advances the wipers 1d1, 2d1 and 3d1 65 one step. The rotary magnet D1 on energizing operates contact 4d1. The opening of contact 125a does not promote any switching operation. Contacts 136a and 148a are opened. These also do not promote any switching operation. Contact 167a is closed and energizes relay RV. Relay RV is a slow-to-release relay and remains 70 operated throughout the incoming impulse trains. Relay RV operates contacts 86rv, 126rv, 137rv, 144rv and 149rv. The opening of contact 144rv 75 does not cause any switching because the earth

applied to contact 135rc remains connected up over the closed contact 145rc1.

When the first impulse is terminated relay A releases. Its contacts are accordingly restored to normal. The rotary magnet D1 is deenergized by the opening of contact 123a. The operation of the other contacts of relay A do not result in any switching. The wipers of the switch D1 now rest in position 1. No special switching operations take place in this position. 10 When relay A receives the next impulse of the first impulse train it energizes again so that the magnet D1 is energized again over contact 123a. This switches the wipers of the switch D1 into position 2. The next impulse advances the switch 15 to position 3. If this is the last impulse of the first impulse train relay A is deenergized for a prolonged period so that relay RV releases. Accordingly relay I, winding b, is energized over the earth, contacts 135rc, 136a, 137rv, 138.1, wiper 20 2d1 in position 3, relay I, battery and earth. Relay I operates its contacts 107.1, 109.1, 138.1, 139.1, 156.1. Contact 138.1 breaks the energizing circuit for winding b of relay I. It does not release, however, because contact 139.1 sets up a 25 locking circuit. Contact 109.1 is switched over and connects the rotary magnet of the switch D2 to the control lead for incoming impulses. Contact 107.1 temporarily connects the rotary magnet D2 to the control circuit for outgoing 30 impulses. Contact 156.1 is opened. When the second impulse train is transmitted to the register relay A responds to these impulses. When relay A energizes for the first time relay RV is energized again over contact 167a and remains 35 energized during the second impulse train. The impulses are repeated to the magnet D2 over the contact 123a. The magnet D2 steps the wipers 1d2, 2d2, and 3d2. A contact 4d2 associated with the magnet is opened only when the magnet energizes. If four impulses are transmitted to the magnet D2 during the second impulse train the wipers are advanced to position 4. At the end of the impulse train relay A remains deenergized for a prolonged period. Consequently relay 40 RV deenergizes. Relay RV causes relay II to energize over winding b over contact 137rv in the following circuit: earth, contacts 135rc, 136a, 137rv, 140.2, wiper 2d2, contact 4 in the bank associated with this wiper, winding b of relay II, 45 battery, earth. Relay II energizes and operates its contacts. At contact 140.2 winding b of relay II is disconnected from contact 137rv. Relay II does not release, however, since contact 141.2 sets up a locking circuit. Contact 108.2 connects 50 magnet D2 to the outgoing control circuit in preparation. Contact 110.2 connects the control circuit for the outgoing impulsing to relay X. Contact 157.2 is opened. Contact 152.2 is closed and establishes the following circuit for winding II of relay Y: earth, contacts 152.2 and 4d1, wiper 3d1 in position 3, contact 158rh, winding 55 II of relay Y, battery and earth. Relay Y energizes and operates its contacts. The operation of relay Y initiates the transmission of the impulse train registered in the switch D1. The transmission can take place while incoming impulses are being received.

In order not to make the understanding of the switching operations unnecessarily difficult those 70 switching operations which occur when impulses are received will be described first.

The third impulse train sent by the calling station may comprise either one or two impulses. If only one impulse is transmitted as the third 75

impulse train this is suppressed. If, however, two impulses are transmitted a signal is transmitted over the contacts *ad* and *Ad* by means of a reversal of potential at the bridge *Sa* which 5 brings about the switching operations serving to connect a special meter to the calling line.

If only one impulse is transmitted to the register as the third impulse train relay *A* operates only once. Relay *X* is energized in the following circuit: earth, *124rq*, *123a*, *122.4*, *121.3*, *110.2*, *112rk*, *118rci*, relay *X*, battery earth. Relay *RV* is energized over contact *167a*. Relay *X* operates its contacts *114x*, *115x*, *116x* and *146x*. Contact *114x* removes a short-circuit about winding *I* 10 of relay *RM*. Contact *115x* prepares an energizing circuit for relay *RM* and contact *116x* prepares a circuit for relay *RK*. The closing of contact *146x* has no significance at present. Through the closing of contact *125a* at the end 15 of the impulse train relay *RK* is energized and relay *X* is held energized in the following circuit: earth, contacts *124rq*, *125a*, contacts *126rv* of the slow release relay *RV* which has not yet released, contact *117rm* contact *116x*, winding *I* 20 of relay *RK*, relay *X*, battery, earth. Relay *RK* operates contacts *112rk* and *166rk*. Contact *112rk* is switched over but does not bring about any switching operations. Contact *166rk* holds relay *RK* energized over its winding *II* and *172rc*. 25 When now relay *RV* releases because no further impulses are transmitted after the first impulse relay *X* releases because its circuit is broken at contact *126rv*. Relay *K*, however, remains energized. The control circuit over which the incoming impulses are transmitted to the register switches is accordingly switched through to the rotary magnet *D3* of the register switch *D3* at contacts *112rk* and *115x*.

When the calling station transmits the fourth impulse train, for example the digit 5, the switch *D3* is advanced five steps. The magnet *D3* is energized over: earth, *124rq*, *123a*, *122.4*, *121.3*, *110.2*, *112rk*, *115x*, *118rm*, rotary magnet *D3*, battery and earth. While the rotary magnet *D3* is being energized relay *RV* energizes again. The switch *D3* steps its wiper *1d3*, *2d3* and *3d3* into position 5. Relay *III* energizes in the same way as did relays *I* and *II* at the end of the impulse train. If the digit 6 is dialled as the last impulse 45 train the magnet *D4* is energized over the following circuit: earth, contact *124r2*, *123a*, *122.4*, *121.3* of the control relay *III* which has energized meanwhile over winding *b*, magnet *D4*, battery and earth. The magnet *D4* steps its wipers 50 *1d4* to *3d4* into position 6. On the first step of the switch *D3* the earth connected to the approach *4d* at contact *135rc* is disconnected from the lead *Ld*. This prevents any further heating of the thermo-relay *Th* in the alternating current repeater since all the impulse trains have been transmitted to the register in the normal way. At the end of the impulse train relay *RV* releases. Relay *IV* energizes over earth, *135rc*, *145rci*, *182.4*, *2d4*, *148a*, *149rv*, winding *b*, battery and earth. It sets up a locking circuit for itself over contact *150.4*. Relay *RQ* is deenergized through the opening of contact *170.4*. Contact *100rq* which opens is shunted by contact *101.4* which closes.

As already mentioned the impulse trains registered in the register switches commence to be transmitted while the incoming impulses are still being received. After the switching of the register switch *D2* relay *Y* was energized over winding *II* and initiated the operation of switch *D1*.

When relay energizes over winding *II* the contacts *105y*, *134y*, *163y*, and *171y* are switched over. Contact *105y* does not promote any switching operation. Contact *134y* connects the adjustable resistance *W14* in parallel with winding *II* of relay *RR* so that the latter relay operates as a slow-to-release relay. This slow-to-release feature of the relay may be controlled by adjusting the resistance *W14*. Contact *163y* switches on relay *RV1* so that the latter operates its contacts. Contact *171y* breaks the circuit for relay *RR* which releases. The release of relay *RR* by opening contact *106rr* causes the magnet *D1* to energize over: earth, *104rc*, *106rr*, *107.1*, rotary magnet *D1*, battery and earth. The magnet *D1* advances its wipers. Contact *132rr* damps the winding *I* of relay *Y* by connecting up resistance *W11*. Contact *88rr* causes an impulse to be transmitted over the lead *Li*. When the magnet *D1* energizes contact *4d1* opens. Relay *Y* (winding *II*) consequently releases. When relay *Y* closes contact *171y* and relay *RR* (winding *I*) energizes again. Relay *RR* opens contact *88rr* and *106rr*. The opening of contact *88rr* terminates the first outgoing impulse. Through the opening of contact *106rr* the *D1* is deenergized. Accordingly contact *4d1* is closed again so that relay *Y* (winding *II*) again energizes over winding *I* in position 4. Relay *Y* again causes relay *RR* to release whereby an impulse is transmitted to the rotary magnet and a further impulse is sent out over the lead *Li*. The interaction between relay *Y* and relay *RR* continues until the wiper *3d1* of the switch *D1* reaches position 11. In this position the circuit for energizing relay *Y* over winding *II* so that relay *Y* remains deenergized for a prolonged period. Through the prolonged deenergizing of relay *Y*, relay *RV1* is caused to release. Relay *RV2* thereupon deenergizes for its circuit is broken at contact *165v1* 40 and contact *160rv2* is closed on the deenergizing of relay *RV2*. A circuit is set up for windings *I* and *II* of relay *RH*. This circuit runs over: earth, battery, windings *II* and *I* of relay *RH*, contact *160rv2*, position 11 of the wiper *3d1*, contact *4d1*, *152.2* and earth. Relay *RH* operates its contacts and sets up a locking circuit for itself over its winding *II* and contact *159rh*. Contact *130rh* removes the damping from winding *I* of relay *Y*. Contact *162rh* opens a point in the 50 circuit over relay *RV1*. Contact *99rh* breaks the circuit over which the impulses are transmitted, to a succeeding device on the advancing of the switch *D1* from position 3 to position 11. Contact *158rh* switches on winding *II* of relay *Y* and the closure of contact *134y* causes *RR* to release. The magnet *D1* receives an impulse over contact *106rr* which brings the wipers of this magnet into position 0. Relay *RV1* does not energize since contact *162h* is opened. On the release of relay *RR* an impulse is not transmitted over contact *88rr* because contact *99rh* is opened. In position 0 of the switch *D1* the circuit for winding *b* of relay *I* is broken so that this relay also releases. In consequence the magnet *D2* is connected to the stepping circuit at contact *107.1*. When wiper *3d1* is set in position 0 the circuit for relay *Y* (winding *II*) is broken. Relay *RH* makes a delayed release. Meanwhile relay *Y* is released so that relay *RR* (winding *I*) is energized again over contact *171y*. Eight impulses are transmitted. This is the complementary number of the number 3 (the number of impulses received) with respect to the number 11 (the number of contacts in the switch). After 70 75

the transmission of the first impulse train the transmission of the second impulse train is initiated by the energizing of relay Y, winding II. This energizing circuit is as follows: earth, 151rq, 4d1, 3d1, 153rq and 4d2, wiper 3d2 in position 4, 158rh, winding II of relay Y, battery and earth. Relay Y energizes and by opening contact 171y deenergizes relay RR. Relay RR energizes the rotary magnet D2 over contacts 106rr, 107.1 and 108.2. The switch D2 steps its wipers to position 5 whereby relay Y deenergizes through the opening of contact 4d2. Relay RR is consequently reenergized. Contact 105rr is opened. When this step is taken by the switch an impulse is transmitted over the lead La2 through the closing of the contact 88rr. The next step of the switch is initiated by the energizing of relay Y (winding II) when the contact 4d2 of the magnet D2 is closed. Relay Y allows relay RR to release again whereupon another impulse is transmitted over contact 88rr, the magnet D2 being advanced at the same time. The stepping and transmission of impulses continues until the switch D2 reaches position 11. In this position relay Y remains deenergized for a prolonged period. Relay RR is energized and contact 88rr is open. The relays RV1 and RV2 which were energized during the impulsive now fall back. When contact 160rv2 closes relay RH energizes. Relay RH opens contact 99rh so that the release of relay RR when the switch D2 is advanced from position 11 to position 0 does not result in an impulse being transmitted by contact 88rr. When the contact 158rh is switched over relay Y energizes again. Relay RR releases and the magnet D2 receives an impulse over contact 106rr which advances the wipers to position 0. In this position winding b of relay II is deenergized. Accordingly, the lead controlled by contact 106rr is connected to the magnet D3 over contact 108.2. Relay Y (winding II) energizes after the release of relay RH which takes place when wiper 3d2 is set in position 0 over the following circuit: earth, contact 151rq, 4d1, 3d1, 153rq, 4d2, 155rq, 4d3, wiper 3d3 in position 5, contact 158rh, relay Y, battery and earth. Relay Y energizes relay RV1 over contact 163y and this energizes relay RV2 over contact 165rv1. Relay RR releases. The magnet D3 receives current over earth, contacts 106rc, 106rr, 107.1, 108.2, 119.3, rotary magnet D3, battery and earth. Magnet D3 advances the wipers from position 5 to position 6. During this stepping an impulse is transmitted over the lead La2 over contact 88rr. Winding I of relay Y and winding II of relay RR are damped during this stepping so that the velocity of the stepping of the switches D1 to D4 and consequently the length of the individual impulses transmitted is adjusted to the requirements of the system in which the register is to work. When in response to the operation of relays Y and RR the switch D3 passes to position 11 in the manner already described apropos of the preceding switches, relay Y after having transmitted six impulses is deenergized for a prolonged period whereupon relays RV1 and RV2 release. Relay RH energizes over contact 160rv2 whereupon the switch D3 is advanced to position 0 by the energizing of winding II of relay Y after contact 158rh has been switched over. No impulse is transmitted at this step. The damping of winding I of relay Y is removed at contact 130rh. At contact 11 of wiper 3d3 the circuit for relay RH is broken. Relay RH releases and sets up the following energizing circuit for relay Y over the back contact 158rh: earth, battery, winding II of relay Y, contact 158rh, wiper 3d4 in position 6, contacts 4d4, 3d3, 4d3, 153rq, 3d2, 4d2, 155rq, 3d1, 4d1, and 151rq and earth. Relay Y causes the switch D4 to be advanced with the aid of relay RR which releases, the stepping of the switch being brought about by the following circuit: earth, contacts 104rc, 106rr, 107.1, 108.2, 119.3, 126.4, magnet D4, battery and earth. Relay III is deenergized when wiper 2d3 is set in position 0. The stepping of switch D4 to position 11 and the transmission of impulses over contact 88rr takes place in the same way as in the case of the stepping of switches D1 to D3. When after having transmitted five impulses the switch D4 reaches position 11 relay F energizes over winding I. Relays RV1 and RV2 release because relay Y remains deenergized for a prolonged time. Contact 102f opens and causes relay RC to release. The following circuit is set up for winding I of relay Y: earth, contact 128f, 129rv1, 130rh, winding I of relay Y, resistance W12, battery and earth. Relay Y energizes and operates the rotary magnet D4 over earth, contacts 104rc, 105y, 107.1, 108.2, 119.3, 126.4, magnet D4, battery and earth. The wipers of the switch D4 pass to position 0. In this position relay F deenergizes. Relay IV only releases when the switch D4 reaches position 0 although the circuit for winding b has already been opened at contact 135rc since a circuit for winding II of relay F has been set up over the back contact 127rc and wiper 1d4. Relay IV is held energized over wiper 1d4 over winding a until the switch D4 reaches the position 0. When contact 102f opens not only is relay RC deenergized, but also relay P, whereupon the impulsive lead Li is disconnected through the restoration of contact 100p to normal. Relay RR does not release during the stepping of the switch D4 from position 11 to position 0, since a locking circuit has been set up for its winding II over contacts 128f (relay F is energized in position 11 of the switch) and 133rr. On account of relay RR being held energized contact 88rr is kept open so that no impulse is transmitted over the lead Li even if contact 100p remains open for a long time. The release of relay P in the switch DW brings about the release of the register so that after relays F and RR have released the register may again be seized for the establishment of further calls. The station which has been selected is now called in any known manner. When the called party replies battery is applied to lead Lb2 in the succeeding devices which are not shown. This connection of battery causes relay Z to energize over its winding II in the following circuit: earth, contact 81z, winding II of relay Z, choke-coil Dr2, contact 53p, lead Lb2, battery and earth in the device which is not shown. Relay Z energizes and locks up over earth, battery, resistance W15, contact 84z, winding I of relay Z, contacts 67q and 31c and earth. Contact 81z opens so that the earth connected to the choke-coil Dr2 over winding II of relay Z is disconnected. Relay R is energized in the following circuit: earth, contacts 30c, 34b, and 24k, contact 181z, relay Th, contact 75h, relay R, resistance W19, battery and earth. Relay R operates its contacts and at contact 55r connects up relay R1. Relay R1 closes contact 59r1 thereby energizing relay T (I) in the following circuit: earth, contacts 30c, 34b, 24k, 181z, 59r1, relay T, battery and earth. Through the energizing of relay R1

alternating current from the source We was connected to contacts 57r1 and 58r1, this resulting in the transmission of alternating current over the line La/Lb for signalling the fact that the 5 called station has replied. When relay T energizes contact 65t short-circuits relay R. Relay R releases and by opening contact 55r brings down relay R1. Relay R1 restores its contacts to normal, thereby terminating the transmission of alternating current over the line La/Lb. When relay R releases relay K energizes over winding II before relay T has released. The circuit passes from earth to battery, resistance Wi5, contact 84z, winding II of relay K, the closed 10 contact 64t, back contact 58r, contact 67q and contact 31c to earth. Relay K locks up at contact 25k. The current over the approach Cd is amplified in that when relay K energizes the following circuit is established: earth, battery, winding II of relay C, contacts 60t, 45s, and 23k, resistance Wi3, approach Cd, contact cd, wiper cm, of the secondary switch MW, lead Lc, winding II of relay MT, winding I of relay MZ, contact 15 11mt and earth. In this circuit relay MZ energizes over winding I and operates its contacts. At contact 21mz relay MZ locks up over winding II in the circuit: earth, contact 11mt, windings I and II of relay MZ, contact 21mz, resistance Wi2, battery and earth. At contact 20mz relay 20 MZ connects the interrupter UN2 to the meter ZB. This circuit passes from earth, interrupter UN2, contacts 11mx, 20mz, and 20mu to the meter ZB, battery and earth. By the operation of the interrupter the fee to be charged for this 25 call is determined while the conversation is in progress. The current strength over Lc is reduced again on the release of relay T through the opening of contact 60t. When the called subscriber replaces his receiver in order to release the call or if he gives the clearing signal in any other way potential is applied to lead La2. Accordingly relay S is energized over winding I. This circuit passes from earth over contacts 28k and 82z, winding I of relay S, choke-coil Dr1, 30 contact 100p, contact 44e, lead La2 to battery in the devices which are not shown. In this case also an alternating current impulse is transmitted over the line La/Lb and in response to this the seized devices in the calling exchange 35 are released in any known manner. During the energizing of relay S the following circuit is established for relay R: earth, contacts 30c, 34b, 46s and 181z, the thermo-relay Th, contact 75h, relay R, resistance Wi9, battery and earth. Relay R causes relay R1 to energize whereupon alternating current from the source We is transmitted over the line La/Lb over contacts 57r1 and 58r1. Relay T (I) is energized over contact 45 59r1, whereupon relay R is short-circuited over contact 65t. Relays R and R1 release. Relay T, however, holds up over contacts 61t, 181z, 46s, 34b, 30c and earth. The alternating current impulse sent back over the leads La and Lb causes a prolonged release impulse to be transmitted from the preceding devices to relay J. When relay J energizes for a prolonged period relay H is energized for a corresponding period and a short-circuit is established for relay E by way of contact 74h such that relay E releases. 50 Relay E operates its contacts and at contact 39e breaks the locking circuit for relay E. At contact 40e the circuit over the approach Cd is broken. In consequence relays C, MT, and MZ release. During the release of MT and MZ the 55 following stepping circuit is established for the

magnet MD of the switch MW: earth, interrupter Un1, magnet MD, contacts 12mt, 18mz, 15mx, the bank associated with wiper em, battery and earth. In this circuit the magnet MD receives impulses until wiper em has reached position 0. 5 During the release of relay MZ contact 20mz is also opened thereby terminating the influencing of the meter ZB. A test during further stepping of the wipers of switch MW into position 0 does not take place because contacts 11mt 10 and 8nr are open. When relay C in the switch MW releases relays B, Q, Z and K are deenergized during the opening of contact 31c. During the closing of contact 69q when relay Q releases the following circuit is set up for winding 15 II of relay S: earth wiper ew, contacts 52p, 69q and wd, winding II of relay S, battery and earth. Contact 49s is closed whereupon the magnet WD is subjected to current. Magnet WD opens contact wd whereupon relay S (winding II) 20 releases. This interaction between magnet WD and relay S continues until wiper ew has reached the rest position.

On the release of relay E contact 44e was opened so that the battery potential promoting 25 the release, connected to lead La2 in the succeeding devices does not find earth in the alternating current repeater (contact 28k). By this means the succeeding devices are restored to 30 normal.

If the release is to be initiated by the calling station relay E is similarly short-circuited by the transmission of a special prolonged release impulse whereupon the release of the call takes place after relay E has deenergized. Contact 40e opens the approach Cd whereupon relays B, Q, Z and K are deenergized through the releasing of relay C and the opening of contact 31c. The switch WD is restored to the rest position in the manner already described through the 40 closing of contact 69q while the switch MW restores to normal through the release of relays MT and MZ. Through the opening of contact 44s and the disconnection of the earth connected to contact 28k from the lead La2 the 45 succeeding devices receive the signal intimating that the calling station has terminated the call.

If in case of the call just described in which the register was seized over the approach Sc the digit 2 had been transmitted to the register in 50 place of the digit 1 the digit 2 is evaluated in a special way. The switching operations in the register are the same as those described in connection with the first call except that through 55 dialling the digit 2 as the third impulse train earth is temporarily connected to the approach Sa whereby relay U energizes over winding II and causes the metering switch ZA to be connected up when the connection is completed, instead of the metering switch ZB. The switching 60 operations which occur in the register when two impulses constitute the third digit are as follows:

On the first impulse of the third impulse train after switches D1 and D2 have been set relay X energizes in the following circuit: earth, contacts 124rq, 123a, 122.4, 121.3, 110.2, 1127k and 113rc1, relay X, battery and earth. Relay X energizes and operates contacts 114x, 115x, 116x and 146. At the same time relay RV is energized over contacts 161a. At the end of the first impulse 70 relay RV does not release because the second impulse is received beforehand. For this reason contact 126r remains closed. At the end of the first impulse the following circuit is set up for relay RK (winding I) and for relay X: earth, 75

contacts 124rq, 125a, 126rv, 117rm and 116x, winding I, relay RK, relay X, battery and earth. Relay RK operates its contacts and breaks the original energizing circuit of relay X at contact 112rk. At contact 166rk relay RK locks up over its winding II. When relay A energizes for the second time relay RM also receives current over the following circuit: earth, contacts 124rq, 123a, 122.4, 121.3, 110.2, 112rk, and 115x, winding I of relay RM, relay X, battery and earth. Relay RM operates its contacts. When the second impulse has ended winding II of relay RM is held energized in series with the magnet D3 (which does not energize) during the closing of contact 125a for a definite time. This circuit passes from earth at contact 124rq over contacts 125c, 126rv, and 118rm, winding II of relay RM, magnet D3, battery and earth. Relay X releases. During the opening of contact 167a after the second impulse has been transmitted relay RV releases. Relay RM remains energized for some time after the release of relay RV and the opening of contact 126rv because its winding I is short-circuited at contact 114x. The following circuit is set up for winding II of relay U: earth, contact 85rm, back contact 86rv, wiper aw, contacts 51p and 76h, winding II of relay U, battery and earth. Relay U energizes. Relay RM releases. The energizing of relay U over winding II causes relay MU in the switch MW to energize by closing contact 80u. In addition a locking circuit is set up for winding I of relay U at contact 80u. This circuit passes from earth over contact 2mr1, relay MU, 10mt, dm, ad, Ad, 80u, 11u, battery and earth. The energizing of winding II of relay U is brought to an end by the opening of contact 85rm. Relay MU connects up the metering switch ZA in preparation at contact 22mu and this metering switch is operated in place of the metering switch ZB when the call is established and relay MZ operates.

The further establishment of the call proceeds in the same way as that described in connection with the first embodiment in that the impulse trains following the third impulse train are transmitted by relay A to the switches D3 and D4. The circuit for energizing magnet D3 passes over earth, contacts 124rq, 123a, 122.4, 121.3, 110.2, 112rk, 115x and 118rm, magnet D3, battery and earth.

Naturally, instead of the evaluating device for the third impulse train comprising relays RM, RK and X a stepping switch or a similarly constructed relay switch could be used, the transmission of particular signals then being made dependent upon more and larger digits.

When the register is seized over another approach, for example over the approach Scl the evaluating device which in the present example comprises relays RM, RK, and X remains inoperative because only four impulse trains are received by the switches D1, D2, D3, and D4. The fact that the register is to be taken into use over the approach Scl is determined in the secondary switch MW as has already been stated in connection with calls over the switch 15 in Fig. 1. In such cases the secondary switch MW is set on a free alternating current repeater, the wiper cm seizing one of the approaches Cd1. For the sake of simplicity the manner of operation when setting up such a call will be described in the following only insofar as it differs from that occurring in the case of the first call to be set up.

When the switch MW is started by transmission of alternating current from the calling station

tion in the manner already described the switch tests on a free approach Cd1 by way of its wiper cm. In this approach a special relay C1 (winding II) is operated. In addition to this relay C1 relay C (winding II) also energizes in series with it. The switching operations in the switch MW are the same as described in connection with the first call. Relay C1 operates its contacts and at contact 18c1 breaks the short-circuit over its winding I. The following locking circuit is established for winding I of relay C1: earth, battery, resistance Wi8, winding I of relay C1, contact 78c1 and earth at contact 3ic. Relay C1 is held energized over this circuit after its winding II has been short-circuited over contact 41e. This short-circuit takes place on the energizing of relay E which occurs as already described when relay B energizes over its winding I. The short circuiting of winding II is effected in order to be able to increase the strength of the current passing over wiper cm of the switch MW when the called party replies, with the maximum efficiency. At contact 19c1 relay P is switched over on to wiper cw1 of the switch DW. The starting of this switch and the testing on a free register takes place in the same way as was described in connection with the first embodiment except that at the approach Scl relay RC1 energizes in series with relay RC. Relay RC1 operates its contacts 111rc1, 113rc1, and 135rc1. Contact 145rc1 breaks the lead to the approach Sd over which the "ready" impulses are transmitted to the succeeding device. By the opening of contact 145rc1 the earth connected to contact 135rc is made dependent upon contact 144rv. Since relay RV which controls contact 144rv is energized during each incoming impulse train and releases at the end of each impulse train a plurality of "ready" impulses can be transmitted from the register. Contact 113rc breaks the energizing circuit of relay X so that the third impulse train sent by the calling station passes to the rotary magnet D3 over the closed contact 111rc and contact 115x which remains closed.

When the register is seized relays RC1 and RC energize as already described and relays RR (winding I) and RQ are energized through the closing of contact 172rc. A "ready" signal is transmitted over earth, contacts 135rc, 114rv and 182.4, wiper 2d4 in position 0, the approach Sd, wiper dw, contacts 54p, 38b, and 181z, the thermo-relay Th, contacts 75h, relay R, resistance Wi9, battery and earth. Relay R on energizing operates relay R1 whereupon the source We of alternating current transmits a "ready" impulse to the calling station. Relay T (I) is energized and short-circuits relay R in the manner previously described. Relay T remains temporarily energised over contacts 61t, 181z, 38b, 54p, wiper dw, approach Sd, wiper 2d4, contacts 182.4, 144rv and 135rc.

When the calling station transmits the first impulse train to the register relay A transmits these impulses to the switch D1. The setting circuit of this switch passes over earth, contacts 124rq, 123a, 122.4, 121.3, 110.2, 109.1, rotary magnet D1, battery and earth. Relay RV is energized at contact 167a and holds up throughout the impulsion. Contact 144rv is opened. Relay RT releases. At the end of the impulse train relay RB falls back whereupon winding b of relay I energized over earth, contacts 135rc, 136a, 137rv and 138.1, and wiper 2d1. Relay I locks up over contact 139.1. When contact 144rv is closed the following circuit is set up: earth, con-

tacts 135rc, 144rv, and 182.4, wiper 2d4, approach Sd, wiper dw, contacts 54p, 38b and 181z, relay Th, contacts 75n, relay R, resistance Wi9, battery and earth. Relay R energizes whereupon relay 5 R1 also energizes. Contacts 51rl and 58rl connect up the source We of alternating current whereupon alternating current is transmitted over the line La/Lb. This signal causes the calling station to commence to transmit the second impulse train. On the energization of relay R1 contact 59rl is also closed so that relay T energizes. Relay T short-circuits relay R so that this relay and also relay R1 release. Relay Q has already been energized over contact 56r, on 15 the first "ready" impulse as was the case with the first embodiment. A locking circuit is set up over contacts 67g and 31c for relays Q and B (winding II).

When relay A receives the second impulse train 20 contact 144rv is opened. In consequence the earth connected to lead Ld at contact 135rc is disconnected so that relay T is released. When the second impulse train has been received by the register and the switch D2 is set, relay RV 25 releases again. Accordingly winding b of relay II is energized over 2d2, contacts 140.2, 131rv, 136a and 135rc. Relay II then holds up over contact 141.2. Through the energizing of relay II the switch D3 is connected up over contact 30 110.2 since contact 111rc1 is closed. Through the closing of contact 144rv after the second impulse train has been received relay R is energized again whereupon relays R1 and T energize. An alternating current impulse is again transmitted 35 to the calling station over contacts 57rl and 58rl to indicate that the register is ready to receive the third impulse train. The energizing of relay T short-circuits relay R so that relay R1 releases and terminates the transmission of 40 alternating current from source We. After relay II has energized in the register the transmission of the impulse train registered in the switch D1 commences in the manner already described through relay Y being energized over contact 45 152.2.

When the third impulse train is transmitted to the register relay T is deenergized through the opening of contact 144rv, whereupon relay R can again be energized for the purpose of transmitting a "ready" impulse when the lead Ld is earthed again after the reception of the third impulse train on the release of contact 144rv. This impulse indicates that the register is in a condition to receive the fourth impulse train. 50 After the switch D3 has been set relay III is energized. When the fourth impulse train is transmitted to the register the wipers of this switch D4 are set in the position selected. When this setting is terminated relay RV falls back whereupon winding b of relay IV is energized over earth and contacts 135rc, 144rv and 182.4, wiper 2d4, contacts 148a and 149rv, relay IV locks up at contact 150.4. At contact 120.4 the magnet D4 is connected up for the purpose of advancing 55 the switch when impulses are transmitted. Contact 101.4 is closed, thereby shunting contact 100rq. Relay RQ releases when contact 170.4 opens. The further establishment of the call is the same as that described in connection with 60 the first embodiment.

It should be pointed out that if the setting up of the call is delayed relay Th becomes operative. Relay Th then releases the register and operates the lamp AL. When the register is seized over 65 wiper cw of the switch DW the release is brought

about by relay Th as was described in connection with the first embodiment by the energizing and subsequent release of this relay, the energizing of relay Th having already initiated the release without it being possible for the calling station 5 to prevent the release by commencing to dial before relay Th has released.

The mode of operation of relay Th differs in the case of the present call in that if selecting impulses are received when relay Th is energized 10 the release is prevented.

The manner in which this happens is that through the energizing of relay RC1 when the register is seized over the approach Sc1, contact 145rc1 is opened. If now after relay Th has energized delayed impulses are transmitted to the register relay RV is energized by relay A over contact 167a. In consequence 144rv is opened so that the earth is disconnected from lead Ld. The thermo relay Th then releases without a 20 short-circuit having been set up for winding II of relay B.

The switching operations which occur when the metering impulse is transmitted on the reply of the called station takes place over the approach Cd1 in the same way as described in connection with the establishment of a call over the approach Cd.

As may be seen from the preceding description the evaluating device comprising relays RM, X 30 and RK is only then taken into use when the register is seized over wiper cw and the approach Sc, only a single revertive impulse being transmitted in this case. If, however, the register is seized over wiper cw1, switching operations take place 35 on the energizing of relay RC1 which cause the connection to be set up without the operation of relays RM, RK and X. In this case a revertive impulse is transmitted to the calling station before each impulse train is to be received.

There is now a third case possible, namely, that in which a revertive impulse is to be transmitted before each impulse train by using the evaluating device, with the exception that the transmission of a revertive impulse, before the 45 impulse train received after the evaluating device has operated, is suppressed.

If the register is to work in this way it must be seized over wiper cw2 by the wiper cw2 being connected up in place of wiper cw1. This is 50 made possible by the operation of contact 1c3 operated on the energizing of relay C3. In this case the alternating current repeater must be seized over the approach Cd2. Relay C1 then energizes in series with relay C3. Through the 55 energizing of relay C2 in series with relays RC1 and RC at wiper cw2 of the register the contacts of relay C2 are also operated when the register is seized. Contacts 146x and 143rm are connected up preparatorily by contact 1c2. Contact 2c2 is closed and renders the opening of contact 113rc1 inoperative. Contact 3c2 is opened and renders the opening of contact 111rc1 inoperative. By rendering contacts 111rc1 and 113rc1 inoperative in the case of the establishment of the present call the evaluating devices RM, RK, and X are set in operation in the same way as when in place of relays RC1, C2 and RC only relay RC energizes. Contact 145rc1 which is connected to wiper 2d4 and thus to the control lead Ld is however operated once in such a way that a revertive impulse is transmitted to the calling station over contact 144rv only before the reception of the first, second, third, and fifth impulse trains.

When relay RV has deenergized after the reception of the second impulse train relays R, R1 and T are energized in the manner already described, thereby transmitting a revertive impulse 5 to the calling station. Relay T remains energized over contacts 61t and 181z and earth on the lead Ld.

On the commencement of the third impulse train contact 144rv is opened. The earth connected to contact 135rc is, however, not disconnected from contact 182.4 since on the first impulse of the third impulse train relay X energizes and contact 146x is closed. The earth connected at contact 135rc thus remains connected 15 over contacts 146x, 1c2, 182.4 to the approach sd and thus to the lead Ld. The energizing circuit for relay X on the first impulse of the third impulse train passes from earth over contacts 124rq, 123a, 122.4, 121.3, 110.2, 112rk, 2c2, relay 20 X, battery and earth. If only one impulse is transmitted as the third impulse train relay A deenergizes at the end of this impulse but relay RV remains up for some time because it is slow-to-release. The following circuit is established: 25 earth, contacts 124rq, 125a, 126rv, 117rm and 116x, winding II of relay RK, relay X, battery and earth. In this circuit relay X remains energized for a moment and energizes relay RK over winding I. Relay RK locks up over winding II at contact 166rk. When relay RV releases the circuit just described is broken at contact 126rv. Relay X releases. Through the release of relay RV contact 144rv is closed so that when contact 146x opened, earth was already connected to contact 135rc at contact 182.4. In this way the transmission of a revertive impulse when the evaluating device has operated is prevented.

When the fourth impulse train is transmitted by the calling station this passes to the rotary 40 magnet D3 over earth and contacts 124rq, 123a, 122.4, 100.2, 112rk, 115x and 118rm. Relay RV is energized again so that the earth on contact 135rc is disconnected from the lead Ld when contact 144rv opens. Relay T releases. When earth 45 is again connected to the lead Ld on the closing of contact 144rv after the switch D3 has been set, a revertive impulse is transmitted in respect of the reception of the last impulse train which operates switch D4.

50 Similar switching operations take place when the third impulse train transmitted from the calling station comprises two impulses. In this case after the reception of the first impulse and after relays X and RK (winding I) have energized relay RV does not deenergize because the reception of the second impulse prevents this. A second impulse transmitted from the calling station then passes over earth and contacts 124rq, 123a, 122.4, 121.3, 110.2, 112rk, and 115x, over relay RM and X to battery and earth.

55 Relay RM energizes. Relay X holds up. Relay RM switches on its winding II over contact 118rm. Contact 143rm is closed and prevents the connection of earth to the approach sd being interrupted. When the second impulse is terminated relay RM receives current over its winding II for a prolonged period. This circuit passes from earth over contacts 124rq, 125a, 126rv and 118rm, relay RM (winding II), magnet D3, battery and earth. The magnet D3 has insufficient current to energize. Relay X releases because its circuit is broken by the opening of contact 123a. Relay RV releases. Only now does relay RM, whose winding I is short-circuited over contact 70 114x, commence to make a delayed release.

The delay period of relay RM is used to connect earth at contact 85rm over contact 86rv, which has released meanwhile, to the approach Sa of the register so that through the energizing of relay U (winding II), relay MU is connected up 5 in the manner already described, thereby causing the meter switch ZA to be connected up. The actual metering and the completion of the release of the connection takes place in the manner already described in connection with the previous 10 example.

What is claimed is:

1. In a telephone system, automatic switches, a register, means for seizing said register and for transmitting thereinto trains of impulses, means in said register for at times transmitting trains of impulses dependent upon all of the received trains of impulses to thereby control said switches to extend a call and for at other times transmitting trains of impulses dependent upon 20 only part of the received trains of impulses to thereby control said switches to extend a call, and means in said register effective only at said other times for determining the value of said last call from another part of the received trains 25 of impulses.

2. A telephone system such as claimed in claim 1 wherein said first part of said received trains of impulses comprises one or more trains of impulses preceding and one or more trains of impulses succeeding said other part of said received trains of impulses.

3. In a telephone system, automatic switches, a register for receiving a predetermined number of call-directing trains of impulses and for transmitting to said switches a corresponding number of trains of impulses dependent upon said received call-directing trains of impulses to thereby control the extension of a call over said switches, means for at times seizing said register and for 40 transmitting thereinto trains of impulses of which said predetermined number of call-directing trains of impulses are only a part, and means in said register for at said times determining from another part of said last trains of impulses 45 the value of a call extended in accordance with said call-directing trains of impulses.

4. In a telephone system, automatic switches, a register, means for seizing said register and for transmitting thereinto a characterizing train of 50 impulses preceded and succeeded by call-directing trains of impulses, means in said register for causing trains of impulses dependent only upon the call-directing trains of impulses to be transmitted from said register to control said switches 55 to extend a call, and means in said register for determining the value of said call from said characterizing train of impulses to enable said register to transmit a characterizing signal in dependence upon the value of said call according to said determination.

5. In a telephone system, automatic switches, a register, means for seizing said register and for transmitting thereinto trains of impulses, means in said register for at times diverting part of the received trains of impulses, means in said register for causing trains of impulses dependent only upon the received trains of impulses which are not so diverted to be transmitted from said register to control the extension of a call over said switches, and means in said register for determining the value of said call from said diverted part of the received trains of impulses to enable said register to transmit a characterizing signal 70 75

in dependence upon the value of said call according to said determination.

6. In a telephone system, a register, means for seizing said register and for transmitting thereinto trains of impulses, means in said register for at times diverting part of the received trains of impulses, means in said register for causing trains of impulses dependent only upon the received trains of impulses which are not so diverted to be transmitted from said register to control the extension of a call over said switches, and means in said register for determining the value of said call from said diverted part of the received trains of impulses and for causing said register to transmit a characterizing signal only if said call, according to said determination, is of a predetermined value.

7. In a telephone system, a register, means for at one time seizing said register and for transmitting thereinto call-directing trains of impulses, means for at another time seizing said register and for transmitting thereinto call-directing trains of impulses and an interposed call-characterizing train of impulses, impulse transmitting devices in said register, call-evaluating means in said register, and means in said register for, at said one time, bringing said transmitting devices successively under the influence of the trains of received impulses to record upon each device in turn the value of a received train and for, at said other time, bringing said transmitting devices successively under the influence of the received call-directing trains of impulses only and for diverting said interposed train upon receipt to said call evaluating means.

8. In a telephone system, a register, an impulse receiving circuit and an impulse transmitting circuit in said register, digit storing devices in said register, call evaluating means in said register, means for seizing said register and for transmitting thereinto trains of impulses, means for at times connecting said storing devices successively to said receiving circuit to receive said trains of impulses and at other times for connecting certain of said storing devices successively to said receiving circuit to receive part of said trains, then for connecting said call evaluating means to said receiving circuit to receive a second part of said trains, and then for connecting the remainder of said storing devices to said receiving circuit to receive a third part of said trains, and means for connecting said storing devices to said transmitting circuit in turn to transmit from said register trains of impulses dependent upon the trains of impulses received by said devices to thereby direct the extension of a call, said call evaluating means effective to function in a manner dependent upon the evaluation of said call as determined from said second part of said received trains of impulses.

9. In a telephone system, automatic switches, control equipment having access to said switches, means for seizing said equipment over any of a plurality of approaches and for transmitting thereinto trains of impulses, means in said equipment for controlling the extension of a call over said switches in accordance with all or part of said trains of impulses, and means in said equipment effective at times in accordance with the approach over which said equipment was seized to determine the value of said call from a part of said trains of impulses.

10. In a telephone system, automatic switches, control equipment having access to said switches, means in said equipment for receiving trains of

impulses and for extending a call over said switches in accordance with all or part of said trains of impulses, means for seizing said equipment over any of a plurality of approaches, and means in said equipment effective in accordance with the approach over which said equipment was seized for transmitting a signal when said equipment is prepared to receive a certain one of said trains of impulses or when said equipment is prepared to receive each of said trains of impulses or when said equipment is prepared to receive certain predetermined ones of said trains of impulses.

11. In a telephone system, automatic switches, a register, means for seizing said register over any of a plurality of approaches and for transmitting thereinto trains of impulses, and means in said register effective in accordance with the approach over which said register was seized for either transmitting trains of impulses dependent upon all of the received trains of impulses to thereby control the extension of a call or for transmitting trains of impulses dependent upon only a part of the received trains of impulses to thereby control the extension of a call over said switches.

12. In a telephone system such as claimed in claim 11, means effective when trains of impulses dependent upon only a part of said received trains of impulses are transmitted from said register to control the extension of a call over said switches for determining from another part of the received trains of impulses the value of said call.

13. In a telephone system, automatic switches, a register, means for seizing said register over any of a plurality of approaches and for transmitting thereinto trains of impulses, said register effective to transmit trains of impulses depending upon all or part of the received trains of impulses to control the extension of a call over said switches, and means in said register effective at times in dependence upon the approach over which said register was seized for determining the value of said call from a part of the received trains of impulses.

14. In a telephone system, automatic switches, a register, means for seizing said register over any of a plurality of circuits and for transmitting thereinto trains of impulses, means in said register effective only if said register is seized over a predetermined one of said circuits for diverting one of the received trains of impulses, means in said register for causing trains of impulses dependent only upon undiverted received trains of impulses to be transmitted from said register to control the extension of a call over said switches, and means in said register for determining the value of said call from said diverted train of impulses.

15. A telephone system such as claimed in claim 14, wherein said first means transmits into said register when said register is seized over said predetermined circuit an additional call characterizing train of impulses to be diverted for said determination.

16. In a telephone system, control equipment having a plurality of primary approaches, a register having a plurality of secondary approaches corresponding to said primary approaches, and means for seizing said control equipment over any one of said primary approaches and for transmitting thereinto trains of impulses, said control equipment effective responsive to said seizure to seize said register over the secondary

approach corresponding to said primary approach, said register effective to receive said trains of impulses and to transmit trains of impulses corresponding to all or part of the received trains of impulses depending upon the secondary approach over which said register was seized.

17. In a telephone system, control equipment having a plurality of primary approaches, a register having a plurality of secondary approaches corresponding to said primary approaches, means for seizing said control equipment over one of said primary approaches and for transmitting thereinto trains of impulses, said control equipment effective responsive to said seizure to seize said register over the secondary approach corresponding to said primary approach, said register effective to receive trains of impulses and to transmit trains of impulses dependent upon all or part of the received trains of impulses, and means in said register effective at times in dependence upon the secondary approach over which said register was seized for making a determination from a part of the received trains of impulses upon which said transmitted trains of impulses are not dependent to enable a signal to be transmitted to said control equipment in accordance with said determination.

18. In a telephone system, lines of different classes, a plurality of registers, each of said registers having a plurality of approaches, automatic switches, means for seizing any one of said lines and for transmitting trains of impulses thereover, and means responsive to said seizure for seizing an idle one of said registers over an approach dependent upon the class of the calling line and for placing said register under control of said calling line to receive said trains of impulses, said register effective in dependence upon the approach over which it is seized to cause a signal to be reverted over said line responsive only to said seizure of said register or to cause a signal to be reverted over said calling line responsive to said seizure of said register and also responsive to the receipt of each of certain consecutive ones of said trains of impulses or to cause a signal to be reverted over said calling line responsive to said seizure of said register and also responsive to the receipt of each of certain non-consecutive ones of said trains of impulses.

19. In a telephone system, automatic switches, control equipment having access to said switches, and means for seizing said equipment and for transmitting thereinto trains of alternating current impulses to extend a call, said equipment effective to cause trains of direct current impulses dependent upon all or part of said trains of alternating current impulses to be transmitted from said equipment to control the extension of said call over said switches, said equipment also effective to cause an alternating current signal to be transmitted to the calling station when said equipment is prepared to receive certain of said trains of alternating current impulses.

20. In a telephone system, a register, a line, means for seizing said line and transmitting thereover trains of alternating current impulses to extend a call, means for receiving said trains of alternating current impulses and for transmitting identical trains of direct current impulses to said register, said register effective in accordance with certain of said trains of direct current impulses to control the extension of said call over said switches, said register also effective to originate a direct current signal when it is

prepared to receive certain of said trains of direct current signals, and means responsive to said direct current signals for transmitting an alternating current signal over said line to said calling station.

21. In a telephone system, automatic switches, junction equipment having access to said switches, a register associated with said junction equipment, line equipment having access to said junction equipment, means in said line equipment for seizing said junction equipment and for transmitting thereinto trains of impulses to influence said register, means in said register for at times transmitting trains of impulses dependent upon only a part of the received trains of impulses to thereby control the extension of a call over said switches from said junction equipment, means in said register for determining the value of said call from another part of the received trains of impulses and for transmitting a signal to said junction equipment if said call is of a predetermined value, and means in said junction equipment for transmitting a signal to said line equipment responsive to the receipt of said first signal.

22. In a telephone system, automatic switches, a register, means for seizing said register to transmit thereinto trains of impulses, said register effective to receive trains of impulses and to control the extension of a call over said switches in dependence upon all or part of said received trains of impulses, means for releasing said register if the first of said trains of impulses is not received within a predetermined time after said seizure, and means in said register effective at times for determining the value of said call from a part of said received trains of impulses upon which said extension of said call does not depend.

23. In a switching system, line equipment individual to a specific line, control equipment accessible to said line equipment, means in said control equipment for receiving alternating current impulses, said line equipment effective responsive to a seizing impulse of alternating current over said line to seize said control equipment, means in said line equipment for extending a connection from said line to said impulse receiving means in said control equipment responsive to said seizure, and means in said line equipment for preventing the completion of said line connection to said impulse receiving means until the cessation of said seizing impulse of alternating current.

24. In a telephone system, automatic switches, a register sender, means for seizing said register sender to extend a call and for transmitting thereto call-directing digits, means for diverting a part of the transmitted digits, said register sender effective to control said switches in accordance only with the digits which are not so diverted thereby to extend said call, and means for determining the value of said call from said diverted part of the transmitted digits.

25. In a telephone system, automatic switches, a register sender, means for seizing said register sender to extend a call and for transmitting thereto call-directing digits, means for diverting a part of the transmitted digits, said register sender effective to control said switches in accordance only with the digits which are not so diverted thereby to extend said call, and means for determining the value of said call from said diverted part of the transmitted digits and for

transmitting a call-characterizing signal in dependence upon said determination.

26. In an automatic telephone system, means for transmitting a succession of call-directing digits, means for diverting a part of the transmitted digits, automatic switches controlled in accordance only with the digits which are not so diverted thereby to extend a call, and means for determining the value of said call from said diverted part of the transmitted digits and for transmitting a call-characterizing signal in dependence upon said determination.

27. In an automatic telephone system, means for transmitting a succession of call-directing digits, means for diverting a part of the transmitted digits, automatic switches controlled in accordance only with the digits which are not so diverted thereby to extend a call, and means for determining the value of said call from said diverted part of the transmitted digits and for transmitting or withholding a call-characterizing signal in dependence upon said determination.

28. In a telephone system, a register adapted to receive a plurality of digits, means for seizing said register over any of a plurality of paths, and means in said register effective in accordance

with the path over which said register was seized for transmitting a signal either when said register is prepared to receive only a certain one of said digits or when said register is prepared to receive each of said digits.

29. In a telephone system, a register adapted to receive a plurality of digits, means for seizing said register over any of a plurality of paths, and means in said register effective in accordance with the path over which said register was seized for transmitting a signal either when said register is prepared to receive only a certain one of said digits or, alternatively, when said register is prepared to receive each of a plurality of said digits.

30. In a telephone system, a register adapted to receive a plurality of digits, means for seizing said register over any of a plurality of paths, and means in said register effective in accordance with the path over which said register was seized for transmitting a signal either when said register is prepared to receive each of said digits or, alternatively, when said register is prepared to receive only certain predetermined ones of said digits.

RUDOLF PFANNSCHMIDT. 25
